UNITED STATES PATENT OFFICE.

JOHN J. CAIN, OF BAYONNE, NEW JERSEY.

LOCOMOTIVE BOILER.

Application filed June 2, 1922. Serial No. 565,348.

To all whom it may concern:

Be it known that I, JOHN J. CAIN, a citizen of the United States, and a resident of Bayonne, county of Hudson, State of New Jersey, have invented new and useful Improvements in Locomotive Boilers, of which the following is a specification.

This invention relates to that class of locomotive boilers described in my application for Letters Patent filed Sept. 25, 1920, under Serial Number 412,806, which comprises narrow hollow sections adequately spaced apart and whose face areas are substantially equal to that bounded by the transverse dimensions of the available space above the running gear of the locomotive.

An object of the invention is to provide a mud chamber at each side of, extending the full length of the boiler and connected to the water legs of the transverse sections: said connections being of such a character as to relieve the connecting nipples of all lateral shocks and strains, the said nipples, when duly expanded, acting to resist pressures tending to separate the flanges and recesses and as communicating passages between the mud chambers and the sections.

Another object is to strengthen the base of the boiler by providing transverse chambers located between and suitably connected, by nipples, to the mud chambers, said transverse chambers having blow-off outlets at their central portions, whereby both sides of the boiler may be simultaneously blown off or cleaned.

A further object is to facilitate the flow of the products of combustion from the furnace and to prevent ashes, &c., lodging on the tops of the transverse sections; to this end the upper and under edges of the sections are bevelled or rounded from their front and rear faces to planes passing flatwise centrally through the sections.

The novel features of the boiler of this invention are illustrated in the accompanying drawings, in which:

Fig. 1, is a longitudinal vertical section illustrating the main features of the invention.

Fig. 2, is a plan view, one half of which shows the top of the boiler and the other half the base of the boiler.

Fig. 3, is an enlarged sectional view showing more particularly the arrangement of the superheater sections.

Fig. 4, is a transverse section of the boiler, taken on the line 4, 4, Fig. 3.

Fig. 5, is a vertical section of two of the transverse boiler sections, taken on the line 5, 5, Fig. 4, showing the improvements in the construction of the same, and

Fig. 6, is an enlarged sectional view of one of the flanged connections between a water leg of a transverse section and a longitudinal mud chamber.

The narrow hollow transverse sections 7, 7, the equalizing drum 8, located at their central upper parts and the connecting nipples 9, 9, are essentially similar to the corresponding parts of my before-mentioned application.

The transverse sections, including all of the steaming sections 7, 7, and the superheating sections 10, and 11, are alike structurally and have supporting legs 12, by which they are securely fastened to side mud chambers 13, which extend the full length of the boiler. These mud chambers 13 are tied together by bracing transverse chambers 14, 14, having nipple connections at their ends with the inner sides of the mud chambers and which provide free passages between them through the nipples 15, 15; said mud chambers 13 and transverse chambers 14, 14, constituting the base of the boiler. Both sides of the boiler may by this arrangement be simultaneously blown out, by applying to the central part of each transverse chamber 14, a discharge pipe 16; all of these pipes 16 may connect with a main discharge pipe or each one may be provided with a blow-off cock 17.

In Fig. 6 is shown the method adopted for providing rigid connections between the water legs and the mud chambers, which consists in forming on the bottom of each water leg 12 a downwardly projecting flange 18, shaped to fit into a recess 19, formed in the upper surface of the mud chamber 13, said flange and recess being preferably circular and concentric with the nipple holes in the water leg and chamber, so they may be tooled at the same time the said holes are. The nipples 20 may be applied and expanded in place through hand holes 21; intimate connections between the nipples and the holes being assured by providing clearances for the nipples in the interior of the flanges 18. By this construction it is seen that the nipple is protected against lateral

shocks and strains, its only function being to hold the parts together against vertical separation and provide a passageway between the mud chamber and water leg. All 5 of the water legs are in this manner fastened to the mud chambers, the nipples of the superheater sections being suitably closed, as for instance by plugs; they necessarily being cut off from the interior of 10 the boiler below the water line.

The improvement in the vertical transverse sections included in this invention consists in making the lower edges of the sections between the water legs and their upper 15 edges taper in form, as clearly shown on Fig. 5, that is by bevelling them from their front and rear faces to planes passing centrally flatwise through the sections, as shown at 22 and 23 respectively in Fig. 5. 20 These bevelled edges allow the hot products of combustion to freely enter the heating passages between the sections, which are adequately spaced apart, and those at the tops of the sections also prevent the accumulation 25 of ashes, &c., thereon.

The sections used as superheaters are in all essential respects similar to the steaming sections, they may be of any suitable number and be located in any desirable part of 30 the boiler. As shown two, 10 and 11 are used, connected by nipples to the other parts of the boiler as are the steaming sections, all of said superheater nipples, with the exception of those entering their upper parts 35 are plugged, or otherwise closed. Sections 10 and 11 are, at their lower ends, connected together by open nipples 24.

The section 10 has its upper end joined, by branch pipes to one end of the dry pipe 40 25, in the drum 8, and the upper end section 11 is similarly joined to a pipe 26 which passes to the throttle valve 27 located on the top of the drum and operated by a rod 28, extending into the cab 29 of the locomotive. 45

Engine supply pipe 30 passes from the

throttle valve 27 to the front end of the locomotive.

Steam from all of the steaming sections 7 enter the drum 8, thence through the dry 50 pipe 25 to the section 10, down this section through nipples 24 into section 11, and passes from this superheater section to the throttle valve 27.

31, designates safety valves lying along 55 the top of the boiler and in communication with the front end of the dry pipe 25.

The furnace back wall 32 directs the gases from the fire on the grate 33 up between the first set of sections to the upper part of the 60 boiler, where the baffle wall 34 directs them downwardly between the next set of sections, from which they flow to be directed upwardly by the baffle wall 35, and again from the top of the boiler down between the 65 last set of sections into the smoke box 36, from which they escape through the chimney 37.

I claim—

A locomotive boiler, comprising narrow 70 hollow sections transversely arranged, having water legs at their side edges and spaced apart to afford vertical heating passages between them, a longitudinal chamber beneath the water legs at each side of the sections 75 and extending the full length of the boiler, nipple connections between the water legs and said chambers, transverse bracing chambers connected at their ends to the inner sides of and spaced apart throughout the 80 length of the longitudinal chambers and a blow-off connection located at the central part of each of the transverse chambers, whereby all parts of a long boiler at both 85 of its sides may be uniformly adequately cleaned.

Signed at New York, county and State of New York, this 25th day of May, 1922.

JOHN J. CAIN.

In the presence of—

JAMES A. HUAM,

J. C. LAWRENCE.
